UNITED STATES PATENT OFFICE.

ALBERT FISHER, OF CHICAGO, ILLINOIS.

LAWN-SPRINKLER.

No. 928,872.

Specification of Letters Patent. Patented July 20, 1909.

Application filed July 31, 1908. Serial No. 446,245.

To all whom it may concern:

Be it known that I, ALBERT FISHER, a citizen of the United States, and residing at Chicago, in the county of Cook and State of Illinois, have invented a new and useful Improvement in Lawn-Sprinklers, of which the following is a complete specification.

This invention relates to improvements in lawn sprinklers and more particularly to a 10 gyratory sprinkler adapted to continuously change the direction of its throw.

Heretofore various kinds of lawn sprinklers have been devised but it has not been usual to provide means for continuously 15 changing the position of the spraying nozzle so that it will deliver water in a plurality of directions in succession but in an irregular sequence.

The object of this invention is to provide 20 means adapted to cause the sprinkling nozzle to move about with a gyratory motion to successively discharge the water in different directions and thereby wet a larger area than has heretofore been possible with a nozzle of 25 this character.

It is also an object of this invention to provide a very cheap and simple construction 30 adapted to be connected to an ordinary garden hose or other source of water supply and under the action of the water pressure to move about and throw water in an irregular course and thereby produce a novel and amusing effect.

The invention consists of the matters hereinafter described in the specification and 35 more fully pointed out and defined in the appended claims.

In the drawings: The figure is a fragmentary, side elevation of a device embodying 40 my invention and showing in dotted lines some of the various positions assumed by the distributing or spraying nozzle.

As shown in said drawings: A indicates the end of a garden hose or other source of 45 water supply, to which is attached by means of any suitable hose coupling B a nozzle a, which is restricted or tapered at its outlet end a'. Connected at one end to said tapered end a' is a flexible pipe C of rubber 50 or any other preferred material and which as shown is provided with a plurality of spiral corrugations c. To the opposite end

of said pipe C is attached a connection C' to which is engaged a bell shaped distributing nozzle D, the mouth or larger end of 55 which is closed by a plate d having a plurality of perforations d' near its circumference but closed at its center.

The operation is as follows: When the device is attached to the source of supply 60 and the water turned thereto, the distributing nozzle D and the pipe C are filled with water under pressure. The water entering the pipe C from the restricted nozzle a' is directed axially of said pipe and therefore 65 tends to create a vacuum or to reduce pressure at the end of said nozzle and adjacent the walls of said pipe. This unequal pressure causes the pipe C to move laterally at this point owing to its spirally corrugated 70 form, which motion is accentuated by the pressure through the pipe acting on the corrugated walls, and said pipe C is thus caused to gyrate and move the nozzle D in various directions. 75

Obviously a sprinkler constructed in accordance with my invention is adapted to cover a maximum amount of area and to produce a very pleasing and amusing effect to the eye. Obviously also many details of 80 form and construction may be varied without departing from the principles of my invention.

I claim as my invention:

1. In a device of the class described the 85 combination with a supply pipe of a sprinkling nozzle, and spirally grooved means connecting said nozzle with said pipe and acting to move the nozzle in a gyratory manner. 90

2. In a device of the class described the combination with a source of supply of an internally tapered nozzle thereon, a spirally corrugated pipe connected with said nozzle, and a distributing nozzle connected to said 95 pipe.

3. In a device of the class described the combination with a supply pipe of a restricted nozzle thereon, an externally spirally corrugated, flexible pipe connected with said nozzle at one end, and a bell shaped sprinkling nozzle connected to the opposite end of said pipe. 100

4. In a device of the class described the

combination with a water supply pipe of a flexible pipe having spiral corrugations molded in its outer surface, means connecting said pipes and tending to reduce the fluid pressure at the inlet end of said corrugated pipe, and a spraying nozzle connected to said flexible pipe and provided with a plurality of apertures near its circumference.

In testimony whereof I have hereunto subscribed my name in the presence of two witnesses.

ALBERT FISHER.
